CLIMBING DEVICE.

1,110,566.

Specification of Letters Patent.

Patented Sept. 15, 1914.

Application filed April 27, 1914. Serial No. 835,310.

To all whom it may concern:

Be it known that I, RICHARD LABORDA, a subject of the King of Spain, residing in the city and county of San Francisco and 5 State of California, have invented a new and useful Improvement in Climbing Devices, of which the following is a specification.

My invention relates to improved climbing devices wherein a tubular member having offset ends is provided with a climbing pulley adapted to engage a suspended rope run through the tube and wound around the said climbing pulley, which is operated by 10 means of oscillating pedals, and is particularly adapted for ascending or descending a suspended rope as a fire escape, or, in ascending or descending from buildings and similar structures in course of erection, and 15 the objects of my invention are, first, to provide improved means for climbing a rope; second to provide improved means for preventing an involuntary descent of the climbing device; third, to provide improved oscillating pedals operating independently 20 and adapted to rotate the wheel and climb the rope; and fourth, to provide independent oscillating pedals which are adapted to operate suitable band brakes as well as the 25 climbing wheel. I accomplish these several features by means of the device disclosed in the drawings forming a part of the present specification wherein like characters of reference are used to designate similar parts 30 throughout the said specification and drawings, and in which—

Figure 1 is a broken side elevation of a device disclosing the offset ends and the seat secured thereto in a position substantially in alinement with the suspended rope above the device; the manner in which the suspended rope is run through the tube and around the pulley; the pawl and ratchet for 40 normally preventing a reverse rotation of the climbing pulley and the manner in which pawls pivotally secured to the under surface of the oscillating pedals are engaged to the ratchets which are in turn secured to the climbing pulley. Fig. 2 is a rear elevation of Fig. 1. Fig. 3 is an enlarged elevation of the climbing pulley disclosing the manner in which the suspended rope passes through the tube and around the climbing pulley, the manner in which the internal ratchet on the said climbing pulley is nor-

mally engaged by a pawl pivotally secured to the frame, the manner in which pivoted pawls on the pedals engage the ratchets secured to the climbing pulley and the manner in which band brakes engage the hub of 60 the climbing pulley and the springs which normally raise each oscillating pedal independently of the other pedal, and Fig. 4, is a broken rear elevation partly in section disclosing the sleeve rotatably mounted upon 65 the frame work of the device, the climbing pulley and the ratchets secured to the outer end of the sleeve and beyond the frame work, and the oscillating pedals loosely mounted on either end of a shaft rotatably 70 mounted within the sleeve.

Referring to the drawings, the numeral 1 is used to designate a vertically disposed tube having upper and lower offset ends 2 and 3, respectively. An open frame 4 is secured to the tube and arranged intermediate of the ends thereof. Rotatably mounted within the frame 4 is a sleeve 5 to which is rigidly secured the climbing pulley 6 provided with an internal ratchet 7 which is 80 normally engaged by means of a pawl 8 pivotally secured to the frame 4 and having connection, by means of a rod 9, with a handle 10 secured to the tube 1. The climbing pulley 6 has a tread around which is wound a suspended rope or cable 12 that passes through the tube 1 and around the pulley 14 set within the tube 1 for the purpose of reducing to a minimum the friction 85 of the said rope 12.

A ratchet 15 is secured to each end of the sleeve 5. A shaft 16 is rotatably mounted within the sleeve 5 and has loosely mounted on either end thereof the oscillating pedals 17. The pedals 17 are normally raised by 90 means of suitable springs 18 loosely wound around the outer ends of the shaft 16, one end of each spring being arranged to engage the frame 4, while the other end thereof engages the pedal 17, so that the tendency of the springs 18 will be to normally retain the pedals 17 in an upper position against lugs 20 which are integral with the said frame 4.

Pawls 21 are pivotally secured to the under side of each pedal 17 and arranged to engage the teeth of the ratchet 15 secured to the outer end of the sleeve 5. Each pawl 21 is provided with an extension 22. Band brakes 24 each have one end secured to a 105

pin 25 of a frame 4 and after passing around the hubs of the climbing pulley 6 has the other end thereof secured to a pin 26 of the lever 27, which normally rests against pins 28 secured on either side of the frame 4. A suitable saddle 30 is adjustably secured to the tube 1 for the support of the operator.

The operation is as follows: The operator is seated upon the saddle 30 and by moving either pedal 17 downwardly alternately causes the pawls 21 thereof to engage the ratchets 15, which are secured to either end of the sleeve 5 to which is also secured the climbing pulley 6. As the pedals 17 are alternately moved downward, the climbing pulley 6 is rotated and climbs the suspended rope 12. As the downward pressure on either pedal 17 is removed, the springs 18 return the pedals 17 upward in readiness for the next downward movement. A continued alternating oscillation of the pedals 17 within a certain arc will cause the pulley 6 to rotate and climb the rope 12.

In order to lower the device either one or both of the pedals 17 are pressed downward until the extension 22 of the pawl 21 engages the band brake lever 27. As there is considerable weight being supported by the pawls 21, considerable pressure is required during a downward pressure of either pedal 17 to dislodge the pawl 21 from the ratchet 15.

A spring 35 is provided between each pedal 17 and the extension 22 of the pawl 21. As the extension 22 is pressed against the band brake 27, the said lever causes the band brake 24 to tightly engage the hub of the climbing pulley 6 before sufficient resistance and pressure can be obtained to release the pawl 21 from the ratchet 15 by means of the extension 22, of the said pawl 21, which is resting against the said band brake lever 27. It is obvious from the above, that the band brake 24 will tightly engage the hub of the pulley 6 before the pawl 21 is disengaged from the ratchet 15.

By means of the handle 10 and the rod 9 the pawl 8 is released from the internal ratchet 7 of the climbing pulley 6. After the said pawl 8 has been released from the ratchet 7 of the pulley 6, the descent of the device may be prevented and controlled by the downward pressure on either pedal 17, which pressure, by means of the band brake lever 27, causes the band brake 24 to engage the hub of the climbing pulley 6 in direct proportion to the amount of the pressure so applied.

In order to release the band brake 24 from the hub and again climb the rope, the pawl 8 is first allowed to engage the internal ratchet 7 of the pulley 6, which will prevent the said pulley 6 from rotating and will support the device. By releasing the downward pressure on the pedals 17, the spring 18 will move the pedals 17 upward and away

from the band brake levers 27 and thereby cause the band brake 24 to release the hub of the climbing pulley 6 and the pawls 21 to again engage the ratchet 15 when the said pedals 17 are again moved downward.

70

Having thus described my invention what I claim as new and desire to secure by Letters Patent is—

1. A climbing device comprising a tube having offset ends; a pulley rotatably mounted on the tube; a suspended rope passing through the tube and around the pulley; and oscillating pedals loosely secured to the tube and adapted to engage and rotate the pulley and cause the same to climb the rope when either pedal is moved downward.

75

2. A climbing device comprising a tube having offset ends; a pulley rotatably mounted on the tube; a suspended rope passing through the tube and around the pulley; and oscillating pedals loosely secured to the tube and adapted to engage and rotate the pulley and cause the same to climb the rope when either pedal is moved downward and to release the said pulley when either pedal is moved upward.

85

3. A climbing device comprising a tube having offset ends; a pulley rotatably mounted on the tube; a suspended rope passing through the tube and around the pulley; oscillating pedals loosely secured to the tube and adapted to engage and rotate the pulley and cause the same to climb the rope when either pedal is moved downward and to release the said pulley when either pedal is moved upward; and means for normally raising the pedals.

95

4. A climbing device comprising a tube having offset ends; a pulley rotatably mounted on the tube; a suspended rope passing through the tube and around the pulley; oscillating pedals loosely secured to the tube and adapted to engage and rotate the pulley and cause the same to climb the rope when either pedal is moved downward and to release the said pulley when either pedal is moved upward; means for normally raising the pedal; and means operated by the pedals and adapted to engage the hub of the pulley for the purpose of controlling the reverse rotation thereof.

105

5. A climbing device comprising a tube having offset ends; a sleeve rotatably mounted in the tube; a pulley secured to the sleeve; a shaft rotatably mounted within the sleeve; pedals loosely mounted upon the shaft; and means adapted to operatively connect each pedal with the pulley when the said pedals move downward and to release the pedals from the pulley when the said pedals are moved upward.

115

6. A climbing device comprising a tube having offset ends; an open frame secured intermediate of the tube; a sleeve rotatably mounted within the tube; a pulley secured

120

125

130

- to the sleeve; a suspended rope passing through the tube and around the pulley; ratchets secured to each end of the sleeve; a shaft rotatably mounted within the sleeve; 5 a pedal loosely mounted upon each end of the shaft; means for normally raising the pedals; a pawl pivotally secured to each pedal and adapted to engage the ratchet on the sleeve, rotate the pulley and cause the 10 same to climb the suspended rope when either pedal is moved downward; and means for normally preventing a reverse rotation of the pulley.
7. A climbing device comprising a tube 15 having offset ends; an open frame secured intermediate of the tube; a sleeve rotatably mounted within the tube; a pulley secured to the sleeve; a suspended rope passing through the tube and around the pulley; 20 ratchets secured to each end of the sleeve; a shaft rotatably mounted within the sleeve; a pedal loosely mounted upon each end of the shaft; means for normally raising the pedals; a pawl pivotally secured to each 25 pedal and adapted to engage the ratchet on the sleeve, rotate the pulley and cause the same to climb the suspended rope when either pedal is moved downward; and a band brake adapted to engage each side of 30 the hub of the pulley and to be engaged by each pedal in its lower position for the purpose of controlling the reverse rotation of the pulley.
8. A climbing device comprising a tube 35 having offset ends; an open frame secured intermediate of the tube; a sleeve rotatably mounted within the tube; a pulley secured to the sleeve; a suspended rope passing through the tube and around the pulley; 40 ratchets secured to each end of the sleeve; a shaft rotatably mounted within the sleeve; a pedal loosely mounted upon each end of the shaft; means for normally raising the pedals; a pawl pivotally secured to each
- pedal and adapted to engage the ratchet on 45 the sleeve, rotate the pulley and cause the same to climb the suspended rope when either pedal is moved downward; and means for normally preventing a reverse rotation of the pulley; and a pawl pivotally secured 50 to the frame and adapted to engage the pulley and normally prevent the reverse rotation thereof.
9. In a climbing device the combination of a vertically disposed tube having offset 55 ends; an open frame intermediate of the tube; a sleeve rotatably mounted within the frame; a pulley having an internal ratchet on the rim thereof and secured to the sleeve; a ratchet on each end of the sleeve; a suspended rope passing through the tube and around the pulley; a shaft rotatably mounted 60 within the sleeve; a pedal loosely mounted upon each end of the shaft; a spring secured to each side of the frame and adapted 65 to normally raise each pedal independently of the other; a band brake adapted to engage each end of the hub of the pulley; a lever secured to and adapted to operate each band brake; a pawl pivotally secured to each 70 pedal and adapted to engage a ratchet on the sleeve, rotate the pulley and cause the same to climb the suspended rope when either pedal is moved downward, and to be released from the ratchet and to engage and 75 operate one of the band brakes when the pedal to which it is secured reaches its lowermost position; and a pawl pivotally mounted upon the frame and adapted to normally engage the internal ratchet on the pulley. 80

In witness whereof I hereunto set my signature in the presence of two subscribing witnesses.
